DESIGN FOR A PERMUTATION PADLOCK

Gyuro E. B. Jakopets, Chicago, Ill.

Application May 25, 1945, Serial No. 119,733

Term of patent 7 years

(Cl. D50—8)

To all whom it may concern:

Be it known that I, Gyuro E. B. Jakopets, a citizen of the United States, residing at Chicago, in the county of Cook and State of Illinois, have invented a new, original, and ornamental Design for a Permutation Padlock, of which the following is a specification, reference being had to the accompanying drawing, forming a part thereof.

Figure 1 is a side elevational view of a permutation padlock showing my new design; Figure 2 is an end elevational view; and Figure 3 is a top plan view thereof.

I claim:

The ornamental design for a permutation padlock, as shown.

GYURO E. B. JAKOPETS.
